UNITED STATES PATENT OFFICE.

HANS THORMEYER, OF BINGARTESMÜHLE, GERMANY.

ROTARY STEAM-ENGINE.

SPECIFICATION forming part of Letters Patent No. 651,616, dated June 12, 1900.

Application filed October 20, 1899. Serial No. 734,155. (No model.)

To all whom it may concern.

Be it known that I, HANS THORMEYER, a subject of the King of Prussia, Emperor of Germany, residing at Bingartesmühle, near 5 Hersfeld, Hesse, Germany, have invented a new and useful Rotary Steam Engine, of which the following is a specification.

My invention relates to improvements in rotatory steam-engines in which the pressure-spaces are formed in such a manner that the slide-wings offer the entering steam a larger surface than in devices hitherto made and in which the slide-wings after closing the entrance-port through which the steam enters are pushed farther outward toward the periphery, so as to offer a still larger surface for better utilizing the expansion of the steam.

In the accompanying drawings, Figure 1 shows in section a side elevation of my improved engine; and Fig. 2 is an end elevation thereof, also in vertical section.

Referring to the drawings, in an annular casing *a*, closed at both sides by the covers *b*, or end pieces *b*, is revolvably mounted a shaft *c*, on which is secured the disk *d*, carrying the slide-wings *e*. These wings are pressed outward by a spiral spring or the like against the outer wall of the casing, so as to follow the form of the pressure-spaces *f*. Those parts of the spaces (or steamways) which are under high pressure and in which the filling takes place are parallel with the outer surface of the disk *d*.

It will be seen that from the inlet-port *i* to the point *g* there will be no outward movement of the wings *e*, as the chamber remains the same in size. The moment the wing reaches *g* the steam is automatically cut off

from *i*, and as it continues to expand as the 40 chamber *f* enlarges so does the surface of the wings *e* acted on by such expanding steam also enlarge. The outlet-ports connecting the steam-chamber with the exhaust *k* are of large size comparatively, as is also 45 the passage *h* itself, whereby almost instantaneous clearance of the exhaust-steam is had and back pressure prevented.

What I claim as new, and desire to secure by Letters Patent, is—

In a rotary steam-engine, the combination with a casing forming an inclosed chamber, of a disk or drum, revolvably mounted in such chamber, and carrying slide-wings *e*, means for keeping the slide-wings *e* pressed outward against the wall of the chamber, two inlet-ports *i*, *i*, a steam-passage leading to each of said ports *i*, a valve located in each of said passages; an exhaust-outlet port adjacent to each of the inlet-ports, the wall-spaces from the outlets to the next inlet abutting against the periphery of the disk or drum, so as to leave no steam-space, and steam-spaces between the drum and casing extending from each of the inlet-ports to the 60 next exhaust-port having the first portion from *i* to *g* of the same size throughout, and the portion from *g* to the next exhaust-port first gradually enlarged, and then gradually contracted, substantially as shown and described.

In witness whereof I have hereunto set my hand in presence of two witnesses.

HANS THORMEYER.
